UNITED STATES PATENT OFFICE

2,478,273

VEHICLE ANTENNA

Harold F. Jenkins, Elmira, N. Y., assignor of one-half to Weston H. Jenkins, Elmira, N. Y.

Application December 11, 1947, Serial No. 790,987

2 Claims. (Cl. 250—33)

1

This invention relates to new and useful improvements and structural refinements in antennae for vehicles such as automobiles, and the like, and the principal object of the invention is to provide a device of the character herein described, which being equipped with greater surface area as compared to antennae of conventional type, will substantially enhance the receptive efficiency of the radio receiver with which the antenna is used.

A further object of the invention is to provide a vehicle antenna which, being adapted for mounting exteriorly of the vehicle, is equipped with means for preventing violent oscillation thereof in the air stream, such as is commonly experienced when the so-called "whip" antenna of conventional type is employed.

Another object of the invention is to provide a vehicle antenna which is simple in construction and which may, if desired, be conveniently associated with the "whip" antenna already in existence.

An additional object of the invention is to provide a vehicle antenna which will readily lend itself to economical manufacture, which will not easily become damaged, and which is otherwise well adapted for the purpose for which it is intended.

With the above more important objects in view, and such other objects as may become apparent as this specification proceeds, the invention consists essentially of the arrangement and construction of parts as illustrated in the accompanying drawing, in which:

Figure 1 is a side elevational view of the invention;

Figure 2 is a cross sectional view, taken substantially in the plane of the line 2—2 in Figure 1;

Figure 3 is a cross sectional view, taken substantially in the plane of the line 3—3 in Figure 2, and;

Figure 4 is an end view, taken in the direction of the arrow 4 in Figure 1.

Like characters of reference are employed to designate like parts in the specification and throughout the several views.

Referring now to the accompanying drawing in detail, the invention consists of a vehicle antenna designated generally by the reference character 10, the same embodying in its construction a bendable rod 11 disposed in a substantially upright position and secured at the lower end portion thereof to a vehicle, while its upper end is provided for purposes of ornamentation with a sphere, or the like, 12.

2

This rod is of the conventional "whip" type, commonly employed as an antenna on automotive vehicles, and the essence of the invention resides in the provision of a frusto-conical receiver 13 which is movably attached to the upper end portion of the rod 11, as will be hereinafter more fully described.

Needless to say, by providing the receiver 13, the surface area of the antenna is considerably increased, thereby substantially enhancing the reception efficiency of the radio receiver with which the antenna is used.

The frusto-conical receiver 13 is open-ended, and is provided in the major end thereof with a 15 diametrically extending bar 14, the latter being, if desired, securely riveted in position, as indicated at 15. The major end portion of the receiver 13 is also formed with a pair of diametrically opposed, vertically aligned slots 16, 17, these 20 being adapted to receive the rod 11, substantially as shown.

A helical spring 18 has the end portions thereof anchored on the mid-portion of the bar 14 as indicated at 19, the spring 18 passing around the 25 rod 11 and thereby retaining said rod in frictional engagement with the bar 14.

Finally, a strip 20, provided in the end portions thereof with longitudinally extending slots 21, 22, is secured to the receiver 13 adjacent the 30 aforementioned slot 17, this being accomplished by providing the receiver with a clamping bolt 23 which is adjustably accommodated by the slot 22 of the strip. The slot 21 of the strip 20 coincides with the slot 17 of the receiver 13, and the rod 11 extends through the slot 21, as will be 35 clearly apparent from the accompanying drawing.

When the invention is placed in use, the receiver 13 is applied to the upper end portion of the rod 11 as has been already explained, and when the associated vehicle is standing still, the rod 11 is vertically disposed, while the axis is the receiver 13 is horizontal.

However, when the vehicle is in motion and when air pressure causes the rod 11 to bend to a 45 position exemplified by the phantom line 24, the flow of air through the receiver 13 will maintain the receiver in a substantially horizontal position, regardless of the amount of bending or deflection to which the rod 11 is subjected. The maintenance of this horizontal position of the receiver 13 is, of course, facilitated by the provision of the slots 16, 17, the rod 11 moving in the direction of the arrow 25 in the slot 16 and in the direction of the arrow 26 in the slot 17, as indicated in Figures 50 55 1 and 3. It will be apparent that in this manner,

violent oscillation of the aerial in the wind stream will be effectively prevented.

It should also be explained that the slot 16 is somewhat longer with respect to the slot 11, the inner end 27 of the latter slot engaging the rod 11 and thereby maintaining the receiver 13 in a horizontal position when the rod 11 is normally upright, as shown in Figure 3.

On some vehicles the rod 11 is mounted in a slanting rather than in an upright position, and accordingly, means are provided for pre-adjusting, so to speak, the receiver 13 to a horizontal position while the vehicle is standing still.

The said means consist of the aforementioned strip 20 which, by virtue of the slot 21, straddles the rod 11. In the event that the rod 11 should be normally disposed in a slanting position as illustrated by the phantom line 28, the screw 23 may be loosened and the strip 20 slid forwardly, that is, in the direction of the arrow 29, so that the inner end 30 of the slot 21, rather than the inner end 27 of the slot 17, engages the rod 11 and normally maintains the receiver 13 in a horizontal position.

It may be noted that while in the foregoing disclosure the rod 11 has been referred to as a component part of the invention, it should be understood that the rod may already be in existence of the vehicle in the form of the conventional "whip" antenna, in which instance the receiver 13, together with the associated mounting means, may be applied to the existing rod in the form of an attachment.

It is believed that the advantages and use of the invention will be clearly apparent from the foregoing disclosure and accordingly, further description thereof at this point is deemed unnecessary.

While in the foregoing there has been shown and described the preferred embodiment of this

invention it is to be understood that minor changes in the details of construction and arrangement of parts may be resorted to without departing from the spirit and scope of the invention as claimed.

Having described the invention, what is claimed as new is:

1. In a vehicle antenna, the combination of a resilient supporting rod adapted to oscillate in a vertical plane from an initial substantially upright position, a horizontally elongated hollow signal receiver open at least at one end, and a pivotal connection attaching at least one point on said open end of said receiver to said rod, said connection having a horizontal axis extending transversely of the receiver, whereby the latter may remain substantially horizontal in an air stream while the rod is inclined from its initial position to prevent formation of undue stresses in said rod.

2. The device as defined in claim 1 together with means for pre-adjusting said receiver relative to said rod, whereby the receiver is substantially horizontal when said rod is in its initial position.

HAROLD F. JENKINS.
